Patented Jan. 21, 1969

213,249

PRESSURE CYLINDER

John B. Winegardner, Columbus, Ohio, assignor to
Lennox Industries Inc., a corporation of Iowa

Filed Jan. 22, 1968, Ser. No. 10,260

Term of patent 14 years

U.S. Cl. D23—2
Int. Cl. D23—01

FIG. 1.

FIG. 2.

FIG. 3.

FIG. 4.

FIG. 1 is a perspective view of a pressure cylinder embodying my new design;

FIG. 2 is a top plan view of the same design;

FIG. 3 is a side elevational view of the same design; and

FIG. 4 is a bottom plan view of the same design.

I claim:

The ornamental design for a pressure cylinder, substantially as shown and described.
